UNITED STATES PATENT OFFICE.

BENJAMIN F. HAUGH, OF ANDERSON, INDIANA.

METHOD OF CASTING KNUCKLES FOR CAR-COUPINGS.

1,078,500.

Specification of Letters Patent.

Patented Nov. 11, 1913.

Application filed August 11, 1910, Serial No. 576,712. Renewed September 9, 1913. Serial No. 788,936.

To all whom it may concern:

Be it known that I, BENJAMIN F. HAUGH, a citizen of the United States, residing at Anderson, in the county of Madison and 5 State of Indiana, have invented certain new and useful Improvements in Methods of Casting Knuckles for Car-Couplings, of which the following is a specification.

In the casting of knuckles for car couplers 10 containing insert wearing strips of hardened metal, as shown and described in Reissue Patent No. 11,704, of November 20, 1898, considerable difficulty has been experienced in locating said insert strips in position to 15 conform accurately to the contour of the draft face of the knuckle and on the exact draft line. That said strips shall be so located is of great importance in the use and service of the knuckle, and the careful work 20 of expert molders has been required to secure the desired result.

The object of my present invention is to 25 simplify the process of casting such knuckles so that said inserts may be accurately located by means that can be employed by any one of ordinary skill, the work greatly facilitated and the expense incident thereto reduced, all as will be hereinafter more fully described and claimed.

30 Referring to the accompanying drawings which are made a part hereof and on which similar reference characters indicate similar parts, Figure 1 is a plan view of a mold formed for the casting of knuckles of the 35 character in question, showing the self-hardening insert wearing plates described in said patent, secured in proper position therein, Fig. 2 a view showing a portion of the pattern used to form said mold, Fig. 40 3 a perspective view of one of said insert plates, and Fig. 4 a similar view of a complete knuckle formed according to my improved method.

In said drawings the portions marked A 45 represent the mold, B the pattern, C the insert plates, and D the finished knuckle.

In carrying out said invention the mold A used is of the same general character usually employed and formed by packing 50 the sand around the pattern within the flask A', in the usual manner. On the pattern B, however, I form a point, or rib b, on the exact draft line of the knuckle so that when said pattern is withdrawn from the sand 55 a mark is left in said sand indicating the said draft line and the location of the cen-

ter of the wearing plates C. In each end of said insert plates C I form a notch, in exactly midway of its width, or directly in line with what is intended for the draft line of the knuckle wearing face. I then anchor each insert within the mold by inserting anchor pins, or nails, c, through said notches into the marks left by the rib b of pattern in the sand. By this means any one of ordinary skill, who can see the marks, can readily secure the insert strips, or plates, in position in the mold so that when the knuckle is cast they will conform exactly to the correct contour of the knuckle and will be 60 so located as to take the draft and wear along the natural line and at the proper position on the face of said plates. By this means the molds are formed with much greater rapidity, and labor of a lower grade 65 of skill and less expensive character can be employed for the purpose, while the result secured is absolutely accurate at all times, a result which could not always be secured by the old method, even with the best skill 70 and care employed. After the knuckle is withdrawn from the mold the projecting ends of the anchor pins, or nails, may be cut off, as indicated in Fig. 3, leaving a smooth 75 wearing surface, perfectly reinforced with 80 the self-hardening metal, as fully disclosed in my patent above mentioned.

Instead of two plates being used in each knuckle, as indicated, the insert may be a single plate, is preferred, or any other number found appropriate and desired.

It will be noted that the insert strip, or plate, does not extend to the extreme ends of the knuckle, in either direction, and that its edges are tapered, so that it is secured in 95 place by the softer metal of the surrounding parts of the casting, which overhang said edges.

Having thus fully described my said invention, what I claim as new and desire to 100 secure by Letters Patent, is:

1. The method of casting car coupler knuckles having insert wearing plates, which consists in forming on the pattern marking points directly on the center or 105 draft line of the face of the knuckle, forming notches in the ends of the wearing plates to be inserted on their center lines, securing said plates in the mold by anchor pins inserted into sand at the points so marked 110 by the pattern and engaging with the notches in said plates, and then pouring

the molten metal into said mold, substantially as set forth.

2. The method of casting car coupler knuckles having hardened insert plates, 5 which consists in forming a pattern with marking points on the mold to determine the line of draft securing said insert plates to said mold by anchor devices inserted in the points so marked and engaging with 10 said plates, and pouring the molten metal into said mold surrounding said insert plates so secured therein, and then cutting the projecting ends of said anchor devices from the face of the knuckle after being formed, 15 substantially as set forth.

3. The method of casting car coupler knuckles with hardened insert plates in its

wearing face comprising fixing by the form of the mold the position of said insert plates in the mold on the draft line of the knuckle 20 and securing them by anchor pins engaging both with said plates and with the mold within the lines of its ends then pouring the metal to surround the edges of said plates, substantially as set forth. 25

In witness whereof, I, have hereunto set my hand and seal at Anderson, Indiana, this 6th day of August, A. D. nineteen hundred and ten.

BENJAMIN F. HAUGH. [L.s.]
